UNITED STATES PATENT OFFICE.

ANTHONY COSTA, OF CLEVELAND, OHIO.

CARBURETER.

1,179,701.

Specification of Letters Patent. Patented Apr. 18, 1916.

Application filed December 24, 1914. Serial No. 878,861.

To all whom it may concern:

Be it known that I, ANTHONY COSTA, a citizen of the United States, and a resident of Cleveland, county of Cuyahoga, and State of Ohio, have invented a new and useful Improvement in Carbureters, of which the following is a specification, the principle of the invention being herein explained and the best mode in which I have contemplated applying that principle, so as to distinguish it from other inventions.

The subject of the present invention is a carbureter or apparatus for vaporizing hydrocarbon fuels and in particular for vaporizing gasoline and even heavier oils, the present device constituting an improvement over that described and claimed in my co-pending application filed October 15, 1914, Serial No. 866,785, certain of the features herein shown being claimed in another co-pending application filed February 11, 1915, Serial No. 7488.

It has long been known that the more finely a hydrocarbon is broken up, the more intimately it can be intermixed with air and the more perfect and combustible is the mixture.

The object of all devices of the present type commonly known as "carbureters", is to break up the liquid fuel, usually by spraying the same from a nozzle in the presence of air and then causing the air to undergo agitation or internal movement which will complete the intermixiture of the particles of fuel with the air.

The present device secures a perfect intermixture of the fuel with the air as is proven by the results obtained with the present device. These results are secured by supplying the fuel to a moving column of air from a plurality of very fine nozzles inclined at an angle to the path of movement of the air.

Other features which contribute to the results which are secured will be described hereafter.

To the accomplishment of the foregoing and related ends, said invention, then, consists of the process and apparatus herein-after fully described and particularly pointed out in the claims.

The annexed drawings and the following description set forth in detail certain means and one mode of carrying out the invention, such disclosed means and mode illustrating, however, but one of various

ways in which the principle of the invention may be used.

In said annexed drawing:—Figure 1 is a central, vertical section through a device illustrating a preferred form of the apparatus which may be used to carry out my improved method of vaporization; Fig. 2 is a horizontal section on the line 2—2 in Fig. 1; Fig. 3 is a transverse vertical section on the line 3—3 Fig. 1; Fig. 4 is a bottom plan view of the device, and Fig. 5 is a section similar to Fig. 3 but showing only a part of the mechanism.

It will be understood that various forms of apparatus may be employed to carry out my improved method of vaporizing liquid fuels and the present apparatus is illustrated for the purpose of showing one suitable construction which has certain advantages such as convenience of adjustment and moderate cost of manufacture.

In Fig. 1 there is shown the usual mixing chamber consisting of a casing 1 which is preferably a vertically disposed chamber 80 and is provided at its bottom with a main air opening 2. The casing 1 is attached at its upper end to the lower end of a fuel supply manifold 3 which will be suitably attached to an internal combustion engine. 85 The upper portion of the mixing chamber 1 is narrowed to form a conduit 4 on the same cross section as the manifold 3 and in this narrow portion there is provided the usual butterfly valve 5 which may be operated by 90 any suitable means such for example as the pivoted lever 6.

Adjoining the mixing chamber 1 is a float chamber 7 in which there is provided a float 8 of any desired construction controlling, through a pivoted lever 9 and a rod 10, a valve 11 adapted to control the flow of fuel through the intake opening 12 in the chamber as is of course well understood in such constructions. Within the 100 mixing chamber there is mounted a fuel supply conduit 15 having a central aperture 16 therein which is connected by means of conduits 17 and 18 with the float chamber. Upon the top of the conduit 15 there is mounted a disk 19 having a central opening therethrough forming a chamber 20 which connects with the passage 16. Disposed concentrically about the center of the disk 19 are a plurality of vertically extending openings 21 which are tapered at their upper and lower ends and which are con-

nected by means of upwardly and outwardly inclined radial slots 22 with the chamber 20 in the center of the disk. In this way fuel is supplied to the openings 21 through 5 which the main air supply is drawn since there is a collar 23 mounted upon an inwardly directed flange 24 in the mixing chamber, such collar being in close contact and in engagement with the outside of the 10 disk 19 and thus forcing the main air supply to pass upward through the holes 21. The action of this column of air which passes upward through these holes is of course to draw out a spray of fuel from 15 each of the several apertures 22 and it will be noted that these apertures or passages are inclined at an acute angle to the direction of movement of the upwardly moving column of air, which facilitates the vaporization 20 of the fuel.

Auxiliary air is supplied to the mixing chamber around the collar 23 from an auxiliary air valve 30 normally seated in an extension 31 of the body of the device by 25 means of a spring 32, such spring acting between an adjusting disk 33 and a cap 34. This spring 32 is coiled about a sleeve 35 which is attached to the valve 30, the upper end of the sleeve being threaded to receive 30 the cap 34 in various adjusted positions where it may be locked by means of a wing nut 36 adjustably mounted upon a rod 37 which extends through an aperture in the sleeve 35 passing down through the auxiliary valve 30 for another purpose which will be explained hereinafter. The adjusting disk may be moved upward or downward to increase or lessen the tension of the spring 32 by reason of its threaded engagement 40 with the member 38 which is attached to the body of the device. A pin 60 attached to the valve 30 and slidably received in a socket in the body 38 prevents rotary movement of the valve 30 during action or adjustment. 45 A spring 71 contacts the serrated edge 72 of the disk 33 and maintains the same in any given position. The operation of the auxiliary air valve 30 will be readily understood and the reason for varying its resistance to 50 opening is of course to cause it to open at various speeds as may be necessary from the action of the motor to which the carburetor is attached. It will be seen that the rod 37 is moved when valve 30 is opened or closed. 55 I have provided means which correlate the action of the auxiliary air valve with a valve which controls the supply of fuel to the spray openings 22. The advantage of such a provision is that in starting, when no auxiliary air is being drawn, it is thus possible 60 to provide a certain amount of fuel at the spray nozzles and to greatly increase the amount of fuel supply when the motor is operating at high speed and is drawing a considerable amount of auxiliary air, thus

maintaining the proper ratio between the amounts of air and gas which are intermixed. For this purpose it is necessary to provide an additional valve in the fuel supply conduit and I preferably use a valve in 70 the shape of a tapered plug 45 which is depressed to seat in a conical seat or depression at the bottom of the chamber 20 formed centrally within the disk 19. This plug 45 is loosely connected to a sleeve 46 by means 75 of the pin and slot illustrated in an enlarged view in Fig. 5 from which it will be seen that the slot 47 is tapered from the center toward either end whereas the pin 48 is of uniform cross section, thus permitting 80 a certain oscillation of the plug with respect to the sleeve and permitting the plug to seat properly at all times. The sleeve 46 is attached to a short rod 49 which is in turn pivoted to a short rocker arm 50 85 which is attached at its other end to a rod 51. A collar 52 extends upwardly from the disk 19 being threaded for engagement with a cap 53 against which the upper end of a spring 54 operates thus tending to retain 90 the valve plug 45 in its lowermost position.

The valve plug 45 is provided with a central aperture 55 (see Fig. 5) which connects with four lateral apertures 56 which in turn open into the chamber 20 formed in the disk 19 and thus give connection between the opening 16 in the fuel conduit and the lateral spray nozzles 22. As the carburetor adjusts itself to various motor speeds, and particularly when passing rapidly from a high speed to a low speed, or the reverse, the plug valve is operated very quickly and would operate as a pump to force too much liquid through the spray nozzles 22 if some relief means were not provided. I provide for 105 such relief to prevent this pump action by allowing a certain amount of play between the sleeves 46 and that portion of the disk in which it slides and this effectually prevents any pumping of the fuel through the 110 lateral nozzles, that is, the sleeve 46 is enough smaller than the hole in the disk to leave a slight space between the same.

The rod 51 passes down through the bottom of the mixing chamber where it is provided with a cap 60 upon which there is disposed a coiled spring 61 operating against a U-shaped bend 62 in a pivoted lever 63, such lever 63 being in the path of movement of the rod 37 and being operated thereby. During ordinary operation at low speed there will be no auxiliary air drawn in, but upon increasing the speed the increased suction opens the auxiliary air valve 20 depressing the rod 37 and with it the lever 63. This lever acts through the spring 61 to depress the rod 51 which in turn through the rocker arm 50 raises the valve plug 45 thus permitting a direct connection 120 between the fuel supply conduit 15 and the 125

lateral spray nozzles 22. It will be noticed that a spring 64 operating against a collar 65 about the lower end of the rod 51 normally maintains the latter in a position to seat the plug valves 45. It will be noticed that the springs 52 and 64 tend to take up any lost motion in the operating levers and thus maintain the valve plug against its seat. The spring 61 is however, made stronger than the combined springs just named and thus causes a lifting action when the lever 63 is depressed.

By my improved method of intermixing liquid fuel with air the fuel is transformed from its ordinary state as a number of very small liquid globules into a perfect vapor which is intimately intermixed with the air. The same proportionate mixture of air and fuel is maintained at all speeds since the mechanical correlation of the action of the auxiliary air valve and the fuel supply valve permit the amount of fuel to be constantly in the same ratio to the amount of air supply.

It will be noticed that the diameter of the inside of the collar 23, is the same as the inside diameter of the upper portion 4 of the mixing chamber. The hollow column of mixed air and fuel which rises from the apertures 21, is thus permitted to pass upwardly through the mixing chamber without at any point restricting its cross-sectional area. In my apparatus the air and fuel are so perfectly intermixed at the spray nozzle, that no further action tending to this result is required.

Other modes of applying the principle of my invention may be employed instead of the one explained, change being made as regards the means and the steps herein disclosed, provided those stated by any one of the following claims or their equivalents be employed.

I therefore particularly point out and distinctly claim as my invention:—

1. In a device of the class described, the combination of a vertically disposed mixing chamber having a main air inlet opening in its bottom, and a vertical collar projecting upward therefrom about such opening; a fuel supply conduit mounted centrally within said collar; a disk mounted upon the upper end of said conduit and closing the space between said conduit and said column, said disk being provided with a vertical aperture therethrough connecting with the opening in said fuel conduit and having also a plurality of equally spaced vertically disposed openings therethrough and being further provided with outwardly extending radial openings connecting said central vertical opening with such last named openings; said mixing chamber having an auxiliary air opening connecting to the space about said collar; a normally closed valve covering such auxiliary air opening and operable by the suction in said chamber; a plug valve controlling the flow of fuel; and connections between said air valve and said plug valve adapted to cause the latter to be opened upon opening of the former.

openings in said disk, said valve being provided with a central opening connecting to said radial openings.

2. In a device of the class described, the combination of a vertically disposed mixing chamber having a main air inlet opening in its bottom, and a vertical collar projecting upward therefrom about such opening; a fuel supply conduit mounted centrally within said collar; a disk mounted upon the upper end of said conduit and closing the space between said conduit and said column, said disk being provided with a vertical aperture therethrough connecting with the opening in said fuel conduit and having also a plurality of equally spaced vertically disposed openings therethrough and being further provided with outwardly extending radial openings connecting said central vertical opening with such last named openings; means for supplying auxiliary air to said mixing chamber about said collar; a valve adapted to control the flow of fuel from said supply conduit to such vertical apertures through said disk; and means adapted to correlate operation of said valve and said means supplying auxiliary air.

3. In a device of the class described, the combination of a vertically disposed mixing chamber having a main air inlet opening in its bottom, and a vertical collar projecting upward therefrom about such opening; a fuel supply conduit mounted centrally within said collar; a disk mounted upon the upper end of said conduit and closing the space between said conduit and said column, said disk being provided with a vertical aperture therethrough connecting with the opening in said fuel conduit and having also a plurality of equally spaced vertically disposed openings therethrough and being further provided with outwardly extending radial openings connecting said central vertical opening with such last named openings; said mixing chamber having an auxiliary air opening connecting to the space about said collar; a normally closed valve covering such auxiliary air opening and operable by the suction in said chamber; a plug valve controlling the flow of fuel; and connections between said air valve and said plug valve adapted to cause the latter to be opened upon opening of the former.

4. In a device of the class described, the combination of a vertically disposed mixing chamber having a main air inlet opening in its bottom, and a vertical collar projecting upward therefrom about such opening, said chamber being of the same size at its top that it is inside said collar; a fuel supply conduit mounted centrally within said collar and adapted to supply fuel laterally to the inside of said collar along a plurality of radial lines; a plug valve adapted to control the flow of fuel through said supply con-

duit; an automatically operated valve adapted to permit the entrance of auxiliary air to said mixing chamber externally of said collar; and means connecting said auxiliary valve and said plug valve and causing opening of the latter upon opening of the former.

5. In a device of the class described, the combination of a vertically disposed mixing chamber having a main air inlet opening in its bottom, and a vertical collar projecting upward therefrom about such opening, said chamber being of the same size at its top that it is inside said collar; a fuel supply conduit mounted centrally within said collar and adapted to supply fuel laterally to the inside of said collar along a plurality of radial lines, said conduit having a conical valve seat therein; a plug valve adapted to normally contact such seat and to control the flow of fuel through said conduit; an automatically operated valve adapted to permit the entrance of auxiliary air to said mixing chamber; connections between said auxiliary air valve and said plug valve correlating movement of the same; and a pivotal connection between said plug valve and said connections, adapting said valve to contact perfectly such seat.

6. In a device of the class described, the combination of a mixing chamber, a fuel supply conduit mounted vertically therein, a disk mounted upon said conduit and having a central chamber connecting with said conduit and a plurality of radially disposed

inclined apertures connecting with such central chamber, the bottom walls of the latter being formed to make a tapered seat, a plug valve adapted to normally rest on such seat, said valve having an aperture therein adapted to register with the opening in said conduit and lateral passages opening into such chamber in said disk.

7. In a device of the class described, the combination of a mixing chamber, a fuel supply conduit mounted vertically therein, a disk mounted upon said conduit and having a central chamber connecting with said conduit and a plurality of radially disposed inclined apertures connecting with such central chamber, the bottom walls of the latter being formed to make a tapered seat, a plug valve adapted to normally rest on such seat, said valve having an aperture therein adapted to register with the opening in said conduit and lateral passages opening into such chamber in said disk, said valve being loosely and slidably mounted in said disk, an auxiliary air supply valve for said mixing chamber, and means correlating the opening of said air valve and said plug valve in said disk.

Signed by me, this 17th day of December, 1914.

ANTHONY COSTA.
